UNITED STATES PATENT OFFICE

102,469

DESIGN FOR A TELEPHONE SWITCHBOARD CHRONOMETER STAND

James J. McCoy, New York, N. Y.

Application October 28, 1936, Serial No. 65,553

Term of patent 3½ years

To all whom it may concern:

Be it known that I, James J. McCoy, a citizen of the United States and resident of the city and State of New York, county of Queens, have invented a new, original, and ornamental Design for a Telephone Switchboard Chronometer Stand, of which the following is a specification, reference being had to the accompanying drawing, forming part thereof.

Figure 1 is a perspective plan view of a telephone switchboard chronometer stand showing my design.

Figure 2 is a rear perspective view.

I claim:

The ornamental design for a telephone switchboard chronometer stand substantially as shown.

JAMES J. McCOY.
